(57) The ornamental design for a novel center spreader adapter tool for toilet paper rolls and paper towel rolls that do not have inner cardboard tubes, as shown and described.

DESCRIPTION

FIG. 1 is a front side view of a toilet paper roll tube insert with a raised spiral rib.

FIG. 2 is a left side view of the toilet paper roll tube insert of FIG. 1.

FIG. 3 is a back side view of the toilet paper roll tube insert of FIG. 1.

FIG. 4 is a right side view of the toilet paper roll tube insert of FIG. 1.

FIG. 5 is a top end view of the toilet paper roll tube insert of FIG. 1.

FIG. 6 is a bottom end view of the toilet paper roll tube insert of FIG. 1.

FIG. 7 is a front side top perspective view of the toilet paper roll tube insert of FIG. 1.

FIG. 8 is a left side top perspective view of the toilet paper roll tube insert of FIG. 1.

FIG. 9 is a back side top perspective view of the toilet paper roll tube insert of FIG. 1; and,

FIG. 10 is a right side top perspective view of the toilet paper roll tube insert of FIG. 1.
